UNITED STATES PATENT OFFICE.

RALPH B. ANNIS, OF NEW YORK, N. Y., ASSIGNOR TO ALART & McGuIRE, OF NEW YORK, N. Y.,
A FIRM.

DESIGN FOR A BOTTLE.

No. 39,840.

Specification for Design.

Patented Feb. 23, 1909.

Application filed January 8, 1909. Serial No. 471,369. Term of patent 14 years.

To all whom it may concern:

Be it known that I, RALPH B. ANNIS, a citizen of the United States, residing in the borough of Brooklyn, county of Kings, city and State of New York, have invented a new, original, and ornamental Design for Bottles, of which the following is a specification, reference being had to the accompanying drawings, forming a part thereof.

I claim:—

The ornamental design for a bottle as shown.

In witness whereof, I have hereunto signed my name in the presence of two subscribing witnesses.

RALPH B. ANNIS.
